[57] **CLAIM**

The ornamental design for a pair of foldable pliers, as shown and described.

DESCRIPTION

FIG. 1 is a front-left-top perspective view of a pair of foldable pliers, showing my new design, wherein the pair of the foldable pliers is in the folded status;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front-left-top perspective view of the pair of the foldable pliers of my new design, wherein the two handles of the pliers are pivoted to the in use status; and,

FIG. 9 is a front-left-front perspective view of the pair of the foldable pliers of my new design, wherein the two bits are respectively pivoted from the two handles.
